Primary Examiner — Michael A. Pratt*Assistant Examiner* — Wendy L Arminio(74) *Attorney, Agent, or Firm* — Wayne V. Harper(57) **CLAIM**

I claim the ornamental design for a lid, as shown and described.

DESCRIPTION

FIG. 1 is a Perspective view of a lid showing my new design in a closed configuration;

FIG. 2 is another Perspective view of the lid of FIG. 1, shown in an open configuration;

FIG. 3 is a right side view thereof;

FIG. 4 is a front view of the lid of FIG. 1;

FIG. 5 is a Back view thereof;

FIG. 6 is a Right-side view thereof;

FIG. 7 is a Left-side view thereof;

FIG. 8 is a Top view thereof; and,

FIG. 9 is a Bottom view thereof.

The broken lines are only for environmental purposes and form no part of the claimed design.

1 Claim, 8 Drawing Sheets(56)
